HAY BALER

Richard R. Eby, Ephrata, and Otto W. Luek, James W. McDuffie, and Edwin B. Nolt, New Holland, Pa., assignors to The Sperry Corporation, New Holland, Pa., a corporation of Delaware

Application October 5, 1953, Serial No. 27,083

Term of patent 14 years

(Cl. D40—1)

Fig. 1.

Fig. 2

To all whom it may concern:

Be it known that we, Richard R. Eby, a citizen of the United States and a resident of Ephrata, Pennsylvania, and Otto W. Luek, James W. McDuffie, and Edwin B. Nolt, all citizens of the United States and residents of New Holland, Pennsylvania, have invented a new, original, and ornamental Design for a Hay Baler, of which the following is a specification, reference being had to the accompanying drawing, forming a part thereof.

Figure 1 is a side elevation of a hay baler embodying our new design.

Figure 2 is a perspective view of the hay baler of our design.

The characteristic features of the design reside in the full line portions.

We claim:

The ornamental design for a hay baler, as shown and described.
